BOILER

Filed Nov. 15, 1926

INVENTOR
Frederic W. Baker
By W. B. Williamson, Atty.

UNITED STATES PATENT OFFICE.

FREDERIC W. BAKER, OF CLAYMONT, DELAWARE.

BOILER.

Application filed November 15, 1926. Serial No. 148,897.

My invention relates to boilers and an object of the invention is to provide a boiler structure including a fire box composed of a plurality of water legs which are bowed or curved to present concave surfaces, towards each other for the purpose of providing stayless water-legs which may be thoroughly cleaned, and which have a sustained capacity.

A further object of the invention is to provide a return tube boiler in which the drum is placed as a unit upon a unit fire-box structure, and one in which the drum shell is extended rearwardly beyond the back tube sheet to form the rear smoke box and top of the combustion chamber.

Another object of the invention is to provide in a boiler structure, a fire-box of four separate chambers, each of which contains water and which are connected with the drum, at the top of the various water legs or chambers, and the bottom of the drum, the return from the radiators being heated at the bottom of the various chambers, thereby permitting the preheating of the water prior to its entrance into the drum.

Other objects of the invention will appear in the following detail description, and in the accompanying drawings wherein:

Figure 1 is a longitudinal section through the boiler.

Figure 2 is a cross section through the boiler.

Referring more particularly to the drawings, 1 indicates the drum of a return tube boiler of approved type, which has a front tube plate 2, rear tube plate 3 and body shell 4. It will be noted by particular reference to Figure 1 of the drawings, that the upper portion 5 of the body shell is extended rearwardly beyond the rear tube plate 3 forming the rear smoke-box and top of the combustion chamber and that the tubes 1' are all of equal length. The drum 1 has a plurality of angle irons 6 riveted or welded thereto, which angle irons are in turn bolted or suitably attached to the upper edges of the walls of the fire-box structure 7 and adapted to receive lagging to prevent escape of smoke or products of combustion. It should be understood that the weight of the body 4 is primarily supported at the front and rear portions of the fire box structure.

The fire-box structure 7 of the boiler comprises the side walls 8 and 9 respectively, each of which is composed of plates 10 and 11. The plates 10 and 11 are rolled to form a circular

arc and are positioned with their concave surfaces facing as clearly shown in Figure 2, of the drawings, to provide sufficient strength without requiring the use of stay bolts, such as ordinarily used with flat plates, and also providing a chamber within the plates 10 and 11 for containing water which is preheated and which passes from the upper edges of the sides 8 and 9 through curved pipes 12 into the drum. The pipes 12 communicate with the water legs or sides 8 and 9 at their highest points, and extend into the drum curving along the inner side of the drum to permit the introduction of the water into the drum at its lowest point.

The front 14 of the fire-box structure is made up of spaced flat plates 15 and 16, which are spaced by suitable distance pieces and stays 17 and provide a water chamber 18. The upper edge of the front is concavely curved for fitting the outer surface of the body shell of the drum, and its side edges are concavely curved for properly fitting the inner surfaces of the sides 8 and 9. The rear side 19 of the fire-box is composed of spaced plates 20 and 21 which may be spaced by suitable distance pieces and stays 22. The fire box door front is indicated by the reference numeral 22'. The plates 20 and 21 like the plates 15 and 16, of the front, are spaced to provide a chamber, as indicated by the reference numeral 24, for containing water and these chambers 18 and 24 have outlet communication with the drum through suitable pipes, one of which is indicated at 25' and shown in Figure 1 at the uppermost part of the chamber 24. The chambers 18 and 24 and the chambers within the plates 10 and 11 have inlet connections at their lowermost points through suitable pipes 25. A drain pipe 26 is provided and communicates with the lowermost portion of the drum and has branch pipes 26' which communicate with the lowermost portion of the water chambers in the walls of the fire box and this drain pipe may be provided with a suitable valve as indicated by the reference numeral 26''. The combustion chamber projects rearwardly beyond the rear end of the drum 1 and permits the double passage of the products of combustion therethrough prior to its delivery to the stack 29.

From the foregoing description, taken in connection with the accompanying drawings, it will be apparent that a boiler structure has been provided wherein the products of com-

bustion will be guided rearwardly into the combustion chamber, and upwardly therefrom through the drum, and that the heating qualities of the products of combustion will be utilized twice for the heating of the water, first, by heating the water in the water legs and second, by heating the water in the drum, as the products of combustion pass through the tubes thereof. The top of the combustion chamber is fitted with fire-brick as shown at 30 or by a horizontally disposed perforated baffle plate, which may be used instead of the bricks, if it is desired. By the fire bricks or baffle plate being disposed as shown, the products of combustion are deflected through the lower group of tubes as shown in Figure 1 and then through the upper group to the stack 29, the travel of the products being indicated by the arrow in Figure 1.

20 It is, of course, to be understood, that the invention may be constructed in various other manners and the parts associated in different relations, and therefore, I do not

desire to be limited in any manner, except, as set forth in the claims hereunto appended. 25

What I claim is:

1. In a fire box structure for a boiler, a wall comprising two outwardly curved, oppositely disposed plates cooperating to provide a water chamber. 30

2. In a boiler comprising a drum and a fire box, outwardly curved plates cooperatively associated to provide chambers forming the side walls of the fire box, and pipes having communication with the highest point 35 of the chambers and the lowest point in the drum.

3. In a boiler comprising a drum and a fire box, outwardly curved plates cooperatively associated to provide chambers forming 40 the side walls of the fire box, and means of communication between the chambers and the drum.

In testimony whereof, I have hereunto affixed my signature.

FREDERIC W. BAKER.
